TELEPHONE SYSTEM.

Application filed May 9, 1924. Serial No. 71,948.

This invention relates to telephone systems and more particularly to trunk circuits for extending telephone connections between automatic telephone exchanges and manual telephone exchanges.

In systems of this type it is often desirable to extend connections from a subscriber in one city to a subscriber in the main exchange of another city or to a subscriber located either in another exchange in that second city or in an exchange in a third city. To this end, trunks are provided between the automatic exchange and a manual toll exchange in the first city from which these various connections may be made by the aid of a so-called tandem toll or "two-number" operator, the expression "two-number" indicating that two numbers are involved in setting up the connection, i. e., one number for the distant city and a second one for the subscriber in that city. Such trunks must, of necessity, be provided with means whereby disturbances, incident to the setting up of the connection through these various exchanges, will not in any way affect the proper functioning of the circuits; i. e., for example, any temporary disconnection in the battery must not interfere with or cause the false operation of supervisory signals such as busy back signals, busy tones, ringing signals, disconnect signals, flashing recall signals, etc. Trunks of this sort leading from an automatic exchange to a manual toll exchange do not depend for their selection on the use of so-called call wire service but are usually automatically selected by a switch in the automatic exchange that picks out the first idle trunk. This trunk is identified at the toll exchange by the lighting of a signal lamp which indicates to the tandem operator that a through connection is desired. The tandem operator, upon receiving such a signal, connects her telephone set to the seized trunk and after having received the details of the call from the so-called machine switching A operator at the automatic exchange, proceeds with the setting up of the connection.

As stated, the wanted subscriber may be located in the main exchange in a distant city which involves the use of but a single trunk line leading thereto and a so-called inward operator thereat, or the subscriber may be located in a second exchange in that

city in which case a second trunk line leading to this exchange and a second so-called B operator are involved. In the first instance, the battery on the line may only be interrupted once, namely, when the connection is extended by the inward operator to the wanted subscriber, whereas, in the second instance, the battery may be interrupted twice; i. e., once when the connection is extended by the inward operator and a second time when it is extended by the B operator as is well known in the art.

It is an object, therefore, of this invention to provide a trunk circuit, for use in the above type of automatic to manual connections, that is equipped with means whereby the essential signal indications are established and function in a uniform manner regardless of the nature of the connections established beyond; i. e., whether such connections extend through one or more exchanges and involve the use of one or more operators and corresponding trunk lines.

Another object is the provision of a trunk circuit of this type having means for transmitting the usual signal indications essential to the proper supervision of the connection on either side of the trunk circuit.

To attain these objects, in accordance with one feature of the invention, means are provided in this trunk circuit whereby, after the usual line and auxiliary signals are lighted, when the trunk is seized and extinguished when the listening key is operated, the line lamp alone is again lighted as a guard signal when the listening key is released and remains lighted until the tandem operator inserts the plug of this trunk into an outgoing trunk line jack.

Another feature is the provision, in this trunk circuit, of means whereby a signal is operated notifying the tandem operator that the connection beyond has been completed to the wanted subscriber's line and that the ringing operations may begin. This ringing signal is operated the moment steady battery is supplied to the trunk circuit when it is connected directly to the subscriber's line by the aid of but a single trunk line and operator at a second exchange, as well as when the connection is completed through additional exchanges with the aid of additional trunk lines and operators regardless of the fact that in setting up the connections

through each of these exchanges an impulse of battery is momentarily supplied. A timing and counting relay arrangement is provided so that this ringing signal will not operate on such impulses but will function only at the proper time, i. e., when a steady supply of battery is finally supplied.

Another feature is the provision of means in the trunk circuit whereby code ringing 10 may be effected upon the operation of a ringing key according to a certain code, whereby a ringing tone is simultaneously transmitted to the machine switching operator or the calling subscriber and whereby 15 the ringing signal is maintained operated during the ringing period.

Another feature is the provision of means whereby the ringing signal is extinguished by the function of the timing relay arrangement 20 when the ringing key is finally released after the sending of code signals provided the subscriber has answered in the meantime by removing his receiver from the hook, whereas if the subscriber has not answered 25 and the key is released, the signal is not extinguished.

Another feature is the provision, of means whereby, when a called subscriber answers, and the ringing signal is extinguished, relays 30 in the trunk circuit are operated to cause the actuation of supervisory signals at the machine switching operator's position as an indication that connection to the wanted subscriber has been completed.

Another feature is the provision of means whereby busy back signals may be transmitted through the trunk circuit to the machine switching operator's position without 40 operating the ringing signals; i. e., the busy back pulses are of such duration and the interval between them is such that the counting and timing relay arrangement prevents the first two impulses from being transmitted as busy back signals, as disturbances caused by the manner of extending the 45 connections beyond may be similar to these two first signals.

Another feature is the provision of means whereby the called subscriber may flash signals 50 at the machine switching operator's position without lighting the ringing signal or causing any other disturbances in the trunk circuit.

Another feature is the provision of means 55 in the trunk circuit for calling the tandem operator before the called subscriber has answered by the flashing of the line and auxiliary signals without operating a disconnect signal.

Another feature is the provision of means 60 in the trunk circuit whereby the disconnect signal is lighted the moment the trunk is released at the machine switching operator's position, and the plug of the trunk is still 65 connected to the jack of the outgoing line,

and whereby the simultaneous operation of a relay causes a disconnect signal to be sent through the outgoing trunk line to the distant operator's position.

Another feature is the provision of means 70 whereby the line and auxiliary signals are lighted after the trunk is seized a second time before the connection beyond of a previous call has been taken down while the disconnect signal, which was lighted as a signal 75 to disconnect this previous connection, remains lighted until the tandem operator has removed the plug from the outgoing trunk line jack.

The invention may be described in connection with the accompanying drawing in which Fig. 1 illustrates at an automatic exchange, a subscriber's line and automatic and manual connecting switches therefor to a machine switching operator's cord circuit; 80 an automatic selector switch and that portion of a two-number trunk which is located at the automatic exchange and terminates at this switch. Fig. 2 illustrates a manual toll exchange and the end of the two-number 85 trunk terminating at a tandem toll operator's position. This figure also illustrates, in diagrammatic form, to the right of the dotted vertical line a main exchange and an inward operator's position thereat and a 90 trunk line leading from this exchange to another exchange at which a B operator is located; also below the dotted horizontal line a trunk leading from the manual toll 95 exchange to a combination inward and B 100 operator at another city.

Referring to Fig. 1, a connection from the machine switching operator A to the calling subscriber's line 10 is indicated diagrammatically and this connection may be made over a line finder LF, a selector S lines of 105 which terminate at a jack such as J in front of the machine switching operator's cords such as A the plug of which may be connected to this jack J. The machine switching operator receives the details of a call from the subscriber at 10 and causes, through means well known in the art, the operation of the switch 20 to select an idle outgoing two-number trunk T over conductors 30 leading 110 to a manual toll exchange and ending in to a plug 140 at a tandem toll operator's position TO. From this manual toll exchange connection may be made to various points such as, for example, through jack 150 to a 115 main exchange 160 located at another city, which for the sake of convenience will be called Providence, and from there directly to a subscriber 161 by means of the plug 162 and jack 163 of the inward operator 10 or by means of jack 164 to another exchange 165 in the same city where an operator BO 120 may extend the connection to a subscriber 166 in this exchange by means of plug 167 and jack 168. On the other hand, a connec- 125

tion may be extended from the tandem toll operator TO by means of a jack 170 to an exchange 171 in another city such as Providence, and from there by means of a combination inward and B operator TBO to a subscriber 172 by means of plug 173 and jack 174.

This invention may be more readily understood if the functions of the trunk circuit T

10 are described in the establishing of a connection between a subscriber 10 and a subscriber at a distant city. It will be sufficient to consider that, in accordance with well known methods employed in automatic telephony, the line of the subscriber at 10 has been connected to the machine switching operator's cord circuit at position A and that this operator has caused the switch 20 to connect the cord circuit to a toll trunk T.

15 The first operation, therefore, in the trunk circuit T upon completion of this connection is, the closing of a circuit through the tip and ring brushes 17 and 18 and corresponding terminals 16 and 19 of the trunk T.

20

25 The first operation, therefore, in the trunk circuit T upon completion of this connection is, the closing of a circuit through the tip and ring brushes 17 and 18 and corresponding terminals 16 and 19 of the trunk T.

relays 21, 27 and 12 are thereby released. Relay 21 further closes a circuit for the high voltage battery through the winding of relay 28, inner left hand armature and front contact of relay 21, resistance 29, outer left hand armature and back contact of relay 31, lower right hand winding of repeating coil 15, ring conductor of trunk T, lower left hand winding of repeating coil 175, resistance 101, inner right hand armature and back contact of relay 102 to a point 103 and also a parallel circuit from lower left hand winding of repeating coil 175 through left hand winding of polarized relay 104 to this point 103 and from this point to the right hand winding of relay 105, left hand armature and back contact of relay 102 upper left hand winding of repeating coil 175, the tip conductor of trunk T, upper right hand winding of repeating coil 15, right hand armature and back contact of relay 31, resistance 32 to ground. The high voltage battery at relay 28 causes the operation of relays 28 and 105, whereas relay 104 does not operate at this time. Relay 28, in operating, connects a ground at its armature and front contact at the low voltage battery side of resistance 11, which ground reverses the flow of current in the circuit through the bridged relay 9 in the cord circuit. The relay 14 does not operate on this reversal as the relation of the windings thereof remain the same. This reversal causes changes to take place in the cord circuit at A to prepare it for supervisions which, however, are outside of the scope of this invention and may be of any standard type well known in the art of telephony for notifying the operator that trunk line has been seized etc.

Relay 105 in operating closes an obvious circuit for relay 106 which in energizing closes a circuit for the auxiliary signal lamp 108 and line lamp 109 as follows: Battery line lamp 109, outer right hand armature and back contact of relay 110, armature and front contact of relay 103, inner right hand make-before-break contacts of relay 110, auxiliary lamp 108 to ground. The lighting of these lamps notifies the tandem operator at TO that trunk T has been seized and that a through connection is desired.

The tandem operator now depresses listening key 112 thereby bridging her telephone set at 113 across the tip and ring conductors 30 of trunk T through the repeating coil 175 and right hand windings of repeating coil 15, and is thus placed in position to obtain the information from the machine switching operator at A for the passing of the call. The operation of the auxiliary contacts 115 of listening key 112 causes relay 110 to operate from battery winding of relay 110, inner left hand armature and

back contact of relay 110, contacts 115, armature and front contact of relay 106, inner right hand make-before-break contacts of relay 110, lamp 108 to ground. The closing of contacts at 131 of the listening key and operation of relay 110 prepares a circuit for relay 116 from battery winding of relay 116 left hand make-before-break contacts of relay 116 contacts 131, outer left hand armature and front contact of relay 110 armature and back contact of relay 104 to ground at the lower armature and back contact of relay 132. The operation of relays 110 and 116 causes locking circuits for themselves as follows: relay 110 directly to ground at its inner left hand make-before-break contacts, armature and front contact of relay 106 and inner right hand armature and front contact of relay 110 to ground whereas relay 116 locks to the same ground through its left hand armature and front contact and outer left hand connection and back contact of relay 137. The operation of relay 110 therefore extinguishes the auxiliary signal lamp 108 by the breaking of the inner right hand make-before-break contacts thereof while the line lamp 109 is extinguished by the opening of the outer right hand armature and back contact. The operation of relay 116 opens at its outer right hand armature and back contact, a circuit for relay 102 to prevent false operation of this relay on the setting up of the connection as will hereinafter be described. Relay 116 also closes at its inner right hand armature and front contact, a starting circuit to the front contact and armature of the pulsing relay 126 for the operation of the counting relays 120, 121, 122, 123 and timing relays 124 and 125. These counting and timing relays will now be used to distinguish between the various supervisory signals that will be received from the circuits beyond, such as busy back signal pulses interruptions in the battery supply due to the manner of extending the connection and steady battery connections which denote that the circuit is completed to a wanted subscriber's line as will hereinafter be described.

If the tandem toll operator now receives the information for passing on the call, and releases her listening key the line lamp is again lighted as a guard signal to indicate this condition. The circuit for the lamp is as follows: battery, lamp 109, normal auxiliary contacts at 131 of listening key 112, outer left hand armature and front contact of relay 110, armature and back contact of relay 104, lower armature and back contact of relay 132 to ground.

The tandem toll operator is, therefore, now ready to insert plug 140 of trunk T into either jack 150 or 170 depending on whether a call is intended for the main exchange 160

in the town of Providence or for an exchange 171 in the town of Worcester. It will be assumed that a called subscriber is located in Providence and, therefore, after having a trunk line assigned and the usual busy test performed on the sleeve on the jack 150 of this trunk line leading to main exchange 160, the tandem toll operator inserts the plug 140 into jack 150. Relay 133 operates from battery resistance 134, left hand winding of relay 133, right hand armature and back contact of relay 135, sleeves of plug 140 and jack 150 to ground. The right hand winding of relay 133 is short-circuited at this time by the right hand armature and back contact of relay 135. Relay 133 in operating closes at its armature and front contact an obvious circuit for relay 132 which now operates and disconnects the tip of the plug 140 from the operator's busy test circuit and completes at the upper armature and front contact, the tip conductor for the trunk T. The operation of relay 132 also extinguishes the guard lamp 109 by the removing of ground at its lower armature and back contact. This ground is transferred at the make-before-break contact at this armature to the armature of the pulsing relay 126, while the disconnect lamp 136 is connected at this armature to a circuit passing through the armature and back contact of relay 104 to the outer left hand armature of relay 110 which relay is, however, operated at this time preventing the lighting of this disconnect lamp. Thus, it will be seen that when the plug 140 is inserted in a jack of an outgoing trunk no lamps are lighted at the trunk T.

If this outgoing trunk to the inward operator IO at exchange 160 is not busy the tandem toll operator TO transmits the wanted subscriber's number to the inward operator IO. As the nature of such trunk lines do not form any part of this invention, the various indications received from the connections beyond will merely be mentioned in so far as they enter in the operation of the trunk T. To fully describe the operations of trunk T under various conditions of the connections beyond it will be assumed that the inward operator at 160 may in one instance connect her plug 162 to jack 163 associated directly with the line of the subscriber at 161 and in another instance to jack 164 associated with a second trunk leading to a B operator BO in exchange 165 where this operator may connect the trunk by means of plug 167 to jack 168 associated with the line of subscriber 166.

If the call is intended for a subscriber 161 the inward operator IO connects her plug 162 to jack 163, battery will be supplied to relay 126 and a circuit for the operation of ringing lamp 137 will be closed in the following manner: As relay 116 is operated at

this time, the operation of relay 126 causes a circuit for the timing relays 124 and 125 to be closed as follows: battery winding of relay 125, left hand armature and back contact of relay 124, left hand armature and front contact of relay 123, outer left hand armature and back contact of relay 121, inner right hand armature and front contact of relay 116, armature and front contact of relay 126 to ground at the make-before-break contact of relay 132. A circuit will also be closed to the same ground for relay 120 as follows: battery right hand winding of relay 120, inner right hand armature and back contact of relay 121, normal make-before-break contacts of relay 122, right hand armature and back contact of relay 123, inner right hand armature and back contact of relay 116, armature and front contact of relay 126 to the ground at relay 132. The operation of relay 120 does not perform any useful function at this time whereas the operation of relay 125 causes the operation of relay 124 from battery winding of 124, armature and front contact of relay 125 over the same path to ground as relay 132. Relay 124, in operating, breaks the original circuit for relay 125 at its left hand armature and back contact and establishes a locking circuit for itself at its left hand armature and front contact. Thus, is relay 125 prevented from again operating as long as relay 126 remains operated. A circuit is now established by the operation of relay 124 from the ground at relay 132 for relay 137 as follows: battery winding of relay 137, right hand make-before-break contacts of relay 137 outer right hand armature and back contact of relay 121, right hand armature and front contact of relay 124, make-before-break contact of relay 125 to ground at 132 over the same path as relay 124 is operated. The ringing lamp 138 is also operated over this circuit from battery through lamp 138, make-before-break contact of relay 137 to ground at relay 132. Relay 137 in operating closes a locking circuit for itself and for the maintenance of lamp 138 lighted at its right hand armature and front contact directly through the front contact and armature of relay 126 to ground at relay 132. The operation of relay 137 also opens at its inner left-hand armature and back contact, the circuit from the back contact of relay 126 to relay 102 to prevent this relay from operating when relay 126 is later released at the operation of the ringing key 140 as will be described hereinafter. Relay 116 is now also released by the opening of the outer left-hand armature and back contact of relay 137. This relay can, therefore, not be again energized during the setting up of this connection nor can the starting circuit for time relays 125 and 124 be again completed through this relay.

Thus, it will be seen that when a connection is made directly through an inward operator to a subscriber at the main exchange 160, the ringing lamp 138 will be operated by the supply of steady battery from this exchange. 70

If, on the other hand, the call is intended for a subscriber such as 166 in another exchange 165, the inward operator IO connects a trunk line terminating in plug 162 to a jack 164 associated with a trunk leading to that other exchange 165 and the operator BO in this exchange in turn connects the plug 167 of this incoming trunk to jack 168 associated with the line of subscriber 166; battery for relay 126 will be but momentarily supplied at the insertion of plug 162 into jack 165 and again supplied steadily when the B operator BO inserts plug 167 in jack 168. This temporary supply of battery which operates relay 126 will not be of sufficient duration to light the ringing lamp 138 until the call is completed to the subscriber's line 166 and it is prevented from operating on this impulse in the following manner: Relay 116 being operated at this time as hereinbefore stated, the first operation of the relay 126 closes the same circuit as hereinbefore described for the operation of relay 125 and this relay in operating closes the circuit for relay 124 which is slow to operate and the release of relay 125 is, therefore, delayed. As relay 125 is slow in releasing, the circuit, through the right-hand armature and front contact of relay 124 and through the make-before-break contacts of relay 125 for relay 137 and lamp 138 is considerably delayed. The release of relay 126 will, therefore, occur before this circuit is completed and thus prevent the ringing lamp 138 from operating. This circuit will therefore never be completed as relay 124 will be released immediately upon the release of relay 126. However, it will be noted that upon the release of relay 126, relay 120 will remain energized over a circuit as follows: battery right hand winding of relay 120, right hand armature and front contact of relay 120, winding of relay 121, right hand armature and back contact of relay 122, right hand armature and back contact of relay 117, make-before-break contacts of relay 132 to ground. This circuit will now operate relay 121 which did not operate on this circuit when relay 126 was operated as it was then short-circuited by the circuit through the armature and front contact of relay 126. When relay 121 operates it transfers at its outer left hand armature and front contact the circuit for relays 125 and 124 to the back contact and armature of relay 126. Relay 126 now remains deenergized until the operator BO inserts plug 117 into jack 160, and the circuit completed at the back contact of this relay will therefore operate the timing relays 124 and 130

125 to release relay 121 and thus restore the counting and timing relay arrangement to normal. This action is as follows: Upon the energization of relay 125 and deenergization of relay 124 and consequent release of 125 a circuit is established for the left hand winding of relay 120, from battery left hand winding of relay 120, left hand armature and front contact of relay 120, 10 inner left hand armature and back contact of relay 121, right hand armature and front contact of relay 124, make-before-break contacts of relay 125, left hand armature and back contact of relay 123, outer left hand 15 armature and front contact of relay 121, armature and back contact of relay 126 to ground at relay 132. This circuit through the left hand winding of relay 120 opposes the circuit through the right hand winding 20 and causes relay 120 to release. Upon the release of relay 120, relay 121 also releases thus breaking the energizing circuit for relay 124 which is thus restored.

When finally the plug 167 is inserted in 25 jack 168 of subscriber 166 steady battery will be supplied over the trunks back to trunk T and operate relay 126. The operation of relay 126 at this time will of course be long enough to permit the lighting of the 30 ringing lamp 138 in the manner already described in connection with the setting up of a call to a subscriber 161. It is thus seen that the temporary application of battery to relay 126 will not cause the operation of 35 ringing lamp 138 and connections through several trunk lines and exchanges beyond may therefore be made and the lamp 138 lights as hereinbefore described only at the connection of steady battery when a final 40 plug of the last trunk is inserted in the jack of the wanted subscriber.

At the lighting of ringing lamp 138, the tandem toll operator TO will ring the wanted subscriber using a code if desirable. 45 When ringing key 141 is operated audible ringing signals will pass back to the machine switching operator's position over condensers 142 and 143 while the ringing current is going out over the trunk lines to the distant city from ringing source 144 and ground at contact 145. On each operation of the ringing key, ground is connected to the right hand locking armature and contact of relay 137 to hold it operated while the ground 50 normally supplied at the front contact and armature of relay 126 is removed by the release of this relay on the operation of ringing key. When relay 126 releases, a circuit is closed for relay 117 as follows: Battery 55 winding of relay 117, inner left hand armature and front contact of relay 137, armature and back contact of relay 126 to ground at relay 132. Relay 117 operates on this circuit and supplies at its inner left hand 60 armature and front contact a ground for 65

holding relay 137 operated while the holding ground is removed each time the ringing key 140 is released and before relay 126 has had time to be operated. The ringing lamp 138 is, therefore, maintained lighted during 70 the code ringing operations. In case the subscriber does not lift his receiver from the hook during a code ringing period, it may be repeated as described as the ringing lamp will in this case be maintained lighted 75 at the end of each code ringing period.

It will be noted that each time relay 117 is operated, a path is also completed at its middle left hand armature and front contact for the operation of timing relays 125 80 and 124 and relay 120. This circuit path serves no purpose unless the subscriber removes the receiver from the hook either during a ringing period or after. In the first case relay 126 will fail to operate at the end of the ringing period and in the second case it will be released the moment the subscriber answers as battery is then removed from the line. The effect of this release of relay 126 is that the ringing lamp 90 will become extinguished in the following manner: It will be noted that upon the release of the ringing key a ground will be supplied for the timing relays from battery winding of relay 125, left hand armature and back contact of relay 124, left hand armature and back contact of relay 123, outer left hand armature and back contact of relay 121, middle left hand armature and front contact of relay 117, contacts 146 95 of ringing key 141 to ground. Relay 125 will operate and cause the operation of relay 124 which in turn causes the release of relay 125 as hereinbefore described and a shunt circuit for relay 117 is now completed from the ground at ringing key contacts 145 to the outer right hand armature and back contact of relay 121 to the battery at the winding of relay 117 which consequently 100 releases. As this relay 117, supplies at this time the only holding ground for relay 137 and ringing lamp 138, this relay will release and lamp 138 extinguished by the opening of the inner left hand armature and front contact of relay 117 when releasing. It will, 105 therefore, be seen that if the subscriber answers and the ringing key is released, ringing lamp 138 will be extinguished as soon as the timing relays 125 and 124 have 110 functioned.

It will be noted that upon the release of relay 137 and with relay 126 also released, a circuit will be completed for relay 102 as follows: battery winding of relay 102, outer right hand armature and back contact of relay 116, outer left hand armature and back contact of relay 137 armature and back contact of relay 136 to ground at relay 132. It should be mentioned that relay 116 has 115 already been released as its circuit was 120

opened at the outer left hand armature and back contact of relay 137 when operated. This circuit therefore operates, as stated, relay 102 which opens the shunt for the left hand winding of relay 105 at its left hand armature and back contact and at its inner right hand armature and back contact opens the shunt to resistance 101. The inclusion of the left hand winding in the circuit 5 bridging the conductors 30 of the trunk T will cause the release of relay 28 which removes the ground on the low voltage battery side of the resistance 11 and the current through relay 14 will therefore be reversed. 10 This reversed current will have the effect in the cord circuit A of extinguishing a guard lamp thereat or perform any other function well known in the art to notify the machine switching operator that the called subscriber 15 has answered. As stated, the resistance 101 for the left hand winding of relay 104 will be opened at the operation of this relay but relay 104 will not operate soon on this current as the current in the right hand winding of this relay opposes it, and is still sufficient to prevent this operation. Relay 20 126 is released when the called subscriber answers and conversation may now begin between the subscriber at 10 and the subscriber at 161 or 166, whichever subscriber is connected. For the sake of review of the situation up to this time, it may be mentioned that during the talking period, relays 25 105, 106, 110, 102, 132, 12, 21 and 27 are operated and all lamps are extinguished. 30 When the called subscriber replaces his receiver on the hook, relay 126 is again energized causing the circuit for relay 102 to be broken at the armature and back contact of relay 126. The release of relay 102 35 restores the shunt circuit around the left hand winding of relay 105 which in turn causes relay 28 to become operated and restore the ground on the low voltage battery side of resistance 11 and thus again cause the reversing of the current to the line at the machine switching operator's position where the proper disconnect guard lamps or 40 signals are again lighted indicating that the called subscriber has disconnected. It will be noted that the disconnect lamp 136 at the tandem toll operator's position TO is not lighted at this time but as soon as the machine switching operator disconnects, ground 45 is removed from the sleeve lead at the brush 26 and terminal 25 so that relay 21 is now released and the release of this relay opens the circuit from the high voltage battery through the resistance 11 to the left hand winding of relay 14. Relay 21 also opens the 50 circuit for relays 27 which on releasing opens the circuit for relay 12 which, however, releases slowly to permit the relays in the cord circuit to function and releases the switch 20. Relay 21 also opens the

circuit from the high voltage battery at relay 28 thus causing the release of relay 105 which in turn causes the release of relay 106 and the release of relay 110. The release of relay 110 closes the circuit for the disconnect lamp 136 as follows: battery lamp 136, lower armature and front contact of relay 137, armature and back contact of relay 104, outer armature and back contact of relay 110 to ground. Lamp 136 when lighted indicates to the tandem toll operator that the machine switching operator has released. 55 It should be noted that a parallel branch of the circuit that operates lamp 136 operates relay 135. The operation of relay 135 opens the shunt circuit for the right hand winding of relay 133. Relay 133, however, does not release but the decreased current in this circuit causes a sleeve relay in the trunk circuit beyond to release and send the proper disconnect signals to the distant station as is well known in the art. The tandem toll operator now removes the plug 140 from jack 150 and relays 133, 132 and 135 are consequently released and lamp 90 136 is extinguished.

If the machine switching operator should disconnect before the called subscriber, the circuits function in the same manner to light the disconnect lamp 136; i. e., the relays 21, 27, 12, 28, 105, 106 and 110 will release in succession causing the lighting of lamp 136 and operation of relay 135. 95

If both the machine switching operator and the called subscriber should disconnect simultaneously, the operation is also the same and it might be mentioned here that the circuit for relay 126 is opened at the left hand armature and back contact of relay 135. This is for the purpose of preventing this relay 136 from shunting the corresponding relay in another trunk circuit that may, in the meantime, i. e., between the lighting of the disconnect lamp 136 and the removal of plug 144, have been connected to a jack 110 in multiple to jack 150 of the same outgoing trunk. 105

If the machine switching operator releases the trunk T before the wanted subscriber has answered, the relays 21, 27, 12, 28, 105, 106 and 110 are released in the same manner as hereinbefore described and the disconnect lamp is lighted. 115

In case the machine switching operator desires to call the tandem toll operator before the wanted subscriber has answered, she operates a flashing key such as 8 in the cord circuit which disconnects relay 9 and reverses the line battery causing the operation of relay 14 in the trunk circuit. Upon the operation of key 8 each winding of relay 14 is included in a separate circuit from ground to battery. These two circuits are equal to each other in all respects save the resistance of the windings of relay 14. 120 125 130

Therefore different currents will flow in these two windings and since the number of turns in each is the same the magnetic effects will be different and though opposed to each other there will be a resultant sufficient to operate the relay. The operation of relay 14 closes the obvious circuit for relay 31 which causes a reversal of current over the conductors 30 for relay 105 as follows: high voltage battery, winding of relay 28, inner left hand armature and front contact of relay 21, resistance 29, right hand armature and front contact of relay 31, upper right hand winding of repeating coil 15, left hand armature and back contact of relay 102, right hand winding of relay 105 to a point 103. From this point 103 in two parallel circuits, one through the left hand winding of relay 104, another through the inner right hand armature and back contact of relay 102 and resistance 101 and from there through inner left hand winding of repeating coil 175 to the ring conductor of the trunk T, lower right hand winding of repeating coil 15, left hand armature and front contact of relay 31, resistance 32 to ground. Relay 105 is thereby released but is immediately energized again at the release of the flashing key at the machine switching operator's position and thus follows the pulses of this flashing key. However, the rate at which this key is operated prohibits the release of relay 106 which is slow to release while the reversal of the originally applied battery causes the operation of the polarized relay 104. This relay closes every time it is operated at its armature and front contact a circuit for the auxiliary signal 108 and line lamp 109 as follows: battery, line lamp 109, normal contacts 181 of listening key 112, outer left hand armature and front contact of relay 110, armature and front contact of relay 104, auxiliary signal 108 to ground. These signals are therefore, flashed in accordance with the operation of the flashing key to notify the tandem toll operator that the machine switching operator desires to communicate some further information. The fact that relay 106 does not release will naturally maintain the relay 110 operated and thus prevent the disconnect signal from operating.

If the machine switching operator flashes the tandem operator after the subscriber has answered, the operation is the same except that relay 102, is operated. This, however, merely opens the shunt circuit for the left hand winding of relay 105 and the shunt circuit through resistance 101 for the left hand winding of relay 104 which has no effect on the operation of this relay in response to the flashing operations.

In case the wanted subscriber desires to call the machine switching operator, he manipulates the switchhook which causes the operation of relay 126 each time the switch-

hook is depressed. The operation of relay 126 causes the release of relay 102 which shunts the left hand winding of relay 105 which in turn causes the release of relay 28 reversal of battery and the corresponding operation of a supervisory lamp at the machine switching operator's cord circuit each time the switchhook is depressed as hereinbefore described.

In case the machine switching operator, after having released, again connects with a trunk T in response to a call from another subscriber before the trunk T has been released by the tandem toll operator from the connection beyond and the relays in this trunk circuit have not been restored to normal, the line lamp 109 and auxiliary lamp 108 will be lighted in addition to the disconnect lamp 136 which remains lighted until the tandem toll operator removes plug 140 from the outgoing line jack. These lamps are lighted by the reoperation of the relays 105 and 106 as in the setting-up of an ordinary connection while the disconnect lamp will remain operated as long as relay 132 is operated and the fact that relay 110 is in normal position; i. e., before the listening key 112 has been operated a second time which will not occur until after the tandem toll operator removes her plug 140 from the circuit beyond. The disconnect lamp 136 will naturally be extinguished in either case.

If, after the tandem toll operator has inserted her plug 140 in jack 150 or 170, it is found that the inward operator IO, the B operator BO, the inward operator IBO or the wanted subscriber at any of these points is found busy, so-called busy back signals are sent to the trunk T. These signals are transmitted to the machine switching operator at A without operating the ringing signal in the trunk T or in any other way disturb or interfere with the condition of the connection extended to the busy point. These busy back signals which are direct current impulses should, of course, be of such frequency as not to be confused with the temporary impulses caused by the extension of the connection to the several trunk lines and exchanges nor should they cause the operation of the ringing lamp 138, yet be capable of producing indications at the machine switching operators' positions which are to be interpreted by them as busy signals.

To produce this effect, the busy back pulses operate and release relay 126 at a certain frequency and the first pulse received operates relay 126 to prepare the following circuit: battery, right-hand winding of relay 120, inner right-hand armature and back contact of relay 121, make-before-break contact of relay 122, right-hand armature and back contact of relay 123, inner right-hand armature and back contact of relay 116, armature and front

- contact of relay 126, to ground at relay 132. A circuit is also closed for the timing relays as follows: battery, winding of relay 125, left-hand armature and back contact of relay 124, left-hand armature and back contact of relay 133, outer left-hand armature and back contact of relay 121 to ground at relay 132 the same as the circuit previously traced. The operation of relay 125 causes the operation of relay 124 as hereinbefore described and the operation of relay 124 causes the release of relay 125 and the extension of the circuit for the ringing lamp 138, but the functioning of these two relays 124 and 125 occupies sufficient time to prevent this circuit through the ringing lamp being completed before the busy back pulse has ceased and relay 126 released. Relay 120, in operating, closes a circuit for relay 121 to ground at relay 132, but this relay does not operate until relay 126 releases, at which time it transfers the circuit from the timing relays to the back contact of relay 126 which causes these relays to release and become again energized, whereas, relays 120 and 121 are held up through this circuit from battery, right-hand winding of relay 120, right-hand armature and front contact of this relay, winding of relay 121, right-hand armature and back contact of relay 122, right-hand armature and back contact of relay 117 to ground at relay 132. The time relays do not, however, have time to extend the circuit through the inner left-hand armature and front contact of relay 121 before relay 126 is again operated at which time they are again released. Relay 121 prepares a circuit for relay 122 so that when relay 126 is again operated, a circuit for this relay is completed from battery winding of relay 122, inner right-hand armature and front contact of relay 121, make-before-break contact of relay 122, right-hand armature and back contact of relay 123, inner right-hand armature and front contact of relay 116, armature and front contact of relay 126 to ground at relay 132. Relay 122, in operating, prepares a locking circuit for itself from the ground at relay 132 over its left-hand armature and front contact. Relay 122, in operating, breaks at its right-hand armature and back contact the holding circuit for relays 120 and 121 which are now released and also prepares at its contact 176, a circuit for relay 123 which, however, is shunted as long as relay 126 is operated. As relay 126 again releases after the second impulse this circuit for relay 123 is effective and relay 123 operates from battery, winding of relay 122, left-hand armature, front contact and contact 176, winding of relay 123, inner right-hand armature and back contact of relay 117 to ground at relay 132. The operation of relay 123 now prepares a circuit for re-
- lay 102 so that when relay 126 again operates on the third impulse, relay 102 is energized as follows: battery, winding of relay 102, right-hand armature and front contact of relay 123, inner right-hand armature and front contact of relay 117, armature and front contact of relay 126 to ground at relay 122. The operation of relay 102 causes a supervisory signal to be lighted to signal the machine switching operator's position as hereinbefore described and the following restoration of relay 126 causes relay 102 to be released which consequently also extinguishes the lamp at the machine switching operator's position. Relays 122 and 123 will now be held up until the tandem toll operator T removes the plug of trunk T from the outgoing jack. The following or fourth busy back impulse in operating relay 126 causes this lamp to be again operated that is, this lamp will flash in response to the following impulses. During this whole operation, if as is the case in same equipments there is any audible busy tone placed on the circuit, it is passed through the condensers 142 and 143 of the trunk T and transmitted to the machine switching operator's telephone set in the usual manner if it is connected at this time to the cord circuit. She will, therefore, in this case receive the first two impulses of busy back tone before the supervisory lamp lights on the busy back pulses.
- What is claimed is:
1. In a telephone system, a trunk circuit comprising signals, means for operating said signals when the trunk is seized, an operator's telephone set, a key for connecting said telephone set to the trunk, and means actuated when the key is operated for disabling said signals and when the key is released for again operating one of said signals only. 100
  2. In a telephone system, a trunk circuit comprising a plurality of signal lamps in a common circuit, a relay operated when the trunk circuit is seized for closing the circuit to light the signal lamps, a key, a second relay, and circuit means whereby the actuation of the key causes the operation of the relay to extinguish the signal lamps and whereby the subsequent release of the key causes the re-lighting of one of said signal lamps. 110
  3. In a telephone system, a trunk circuit, an operator's position at the incoming end of said trunk circuit for seizing the same, signals in said trunk circuit at said position, means for operating said signals when the trunk is seized at the outgoing end, and means for disabling said signals when the trunk is seized by the operator and re-operating one of said signals when a trunk is released by the operator. 120
  4. In a telephone system, a trunk circuit, an operator's position at the incoming end 130

- of said trunk circuit for seizing the same, signals in the trunk circuit at said position, means for extending said trunk circuit at the incoming end, means for operating said signals when a trunk is seized at the outgoing end, means for disabling the signals when the trunk is seized by the operator and re-operating one of said signals when the trunk is released by the operator, and means for disabling said re-operated signal when a trunk line is extended at the incoming end. 5. In a telephone system, a trunk circuit comprising signals, means for operating said signals when the trunk is seized, a key, means for disabling said signals when the key is operated and re-operating one of said signals when the key is released, and means for disabling said re-operated signal when the trunk circuit is extended. 10. In a telephone system, a trunk circuit, means for connecting said trunk circuit to a wanted subscriber's station, a signal operated when a wanted subscriber's line has been connected with said trunk circuit, a key in said trunk circuit, a source of current connected by the actuation of the key in the trunk circuit for ringing the seized subscriber's station, and means in said trunk circuit controlled by the operation of the key for maintaining said signal operated during the operation of the key and until the wanted subscriber answers and the key is released. 15. In a telephone system, a trunk circuit comprising a signal, means operating said signal when battery is supplied to the trunk circuit, a key for controlling said operating means to maintain the said signal operated when the key is actuated to remove the battery supply from said signal operating means and means for disabling said signal when the key is released and the battery is removed from the trunk circuit. 20. In a telephone system, a subscriber's line, a trunk circuit adapted for connection with said subscriber's line comprising a signal responsive to the connection of said trunk circuit with said subscriber's line, a source of ringing current, a key for transmitting ringing current to the subscriber on said line, means responsive to the actuation of the key for maintaining said signal operated while ringing current is transmitted, means for disabling said signal when the key is returned to normal position and when the subscriber answers the call. 25. In a telephone system, a subscriber's line, a trunk circuit adapted for connection with said subscriber's line comprising a signal, means for actuating said signal responsive to the connection of said trunk circuit with said subscriber's line, a source of ringing current, a key for transmitting ringing currents to call the subscriber on said line, and means for transferring the control over said signal from the means for actuating it to the key to maintain the signal actuated when the key is actuated and to disable the signal when the key is released if the subscriber on the seized line answers the call, and means for transmitting a signal indication to the outgoing end of said trunk line when the key is released and the subscriber answers. 30. In a telephone system, a trunk circuit comprising a signal, means operating said signal when battery is supplied at the incoming end of said trunk circuit for a certain period, a key for controlling said operating means to maintain said signal operated independent of said battery supply, means for returning said signal operating means under control of said battery supply if the key is returned to normal and for disabling the signal if the battery is removed, and means for establishing a signal indication at the outgoing end of the trunk circuit when the signal is disabled. 35. In a telephone system, a trunk circuit comprising a signal, means operating said signal when battery is applied at the incoming end of said trunk circuit for a certain period, a key for controlling said operating means to maintain said signal operated independent of said battery supply, means for returning said signal operating means under control of said battery supply if the key is returned to normal and for disabling the signal if the battery is removed for a certain period and means for establishing a signal indication at the outgoing end of the trunk circuit when the signal is disabled. 40. In a telephone system, a trunk circuit comprising a signal, means for operating said signal if battery is applied at one end of said trunk for a certain period of time, and means for disabling said signal and for transmitting signal indications to the other end of said trunk circuit if battery is removed for a certain period. 45. In a telephone system, a trunk circuit comprising a signal, means for operating said signal when battery is supplied at the outgoing end of said trunk circuit for a certain period. 50. In a telephone system, a trunk circuit comprising a signal, means for operating said signal if battery is applied at one end of said trunk for a certain period of time, and means for disabling said signal and for transmitting signal indications to the other end of said trunk circuit if battery is removed for a certain period. 55. In a telephone system, a trunk circuit comprising a signal, means for operating said signal if battery is applied at one end of said trunk for a certain period of time, and means for disabling said signal and for transmitting signal indications to the other end of said trunk circuit if battery is removed for a certain period. 60. In a telephone system, a trunk circuit comprising a signal, means for operating said signal if battery is applied at one end of said trunk for a certain period of time, and means for disabling said signal and for transmitting signal indications to the other end of said trunk circuit if battery is removed for a certain period. 65. In a telephone system, a trunk circuit comprising a signal, means for operating said signal if battery is applied at one end of said trunk for a certain period of time, and means for disabling said signal and for transmitting signal indications to the other end of said trunk circuit if battery is removed for a certain period.

tain period, means for preventing said signal operating means from operating if battery is applied to said trunk circuit for a shorter period, means for transmitting signal indications to the outgoing end of said trunk circuit if battery is applied at the incoming end of the trunk circuit in impulses of a certain duration and at a certain interval of time between said impulses provided that at least three impulses have been received.

15. In a telephone system, a trunk circuit comprising means for completing a circuit in said trunk circuit if battery is supplied for a certain period and means for preventing said circuit from being completed and for completing another circuit in said trunk circuit at the third impulse of battery if said impulses are supplied at a certain frequency.

20. 16. In a telephone system, a trunk circuit comprising two circuits, means for completing one of said circuits if battery is supplied to said trunk circuit for a certain period and for preventing it from being completed and for completing the other circuit on the third and each succeeding impulse of battery if said impulses are supplied at a certain frequency.

25. 17. In a telephone system, a trunk circuit comprising two circuits, means for completing one of said circuits if battery is supplied to said trunk circuit for a certain period, and means for preventing said circuit from being completed and for completing the other circuit when battery is supplied in impulse of shorter duration after said impulses have occurred at least three successive times at a certain frequency.

30. 18. In a telephone system, a trunk circuit comprising two signaling means, a relay, means for completing a circuit for the operation of one of said signaling means; if said relay remains operated a certain period of time, and means for completing another circuit for the operation of the other signaling means if said relay is operated a certain number of times when the periods of operation are of shorter duration.

35. 19. In combination, a relay, a circuit operated thereby, and a time relay arrangement for extending said circuit in one direction if said relay is operated a certain period of time and for extending said circuit in another direction if said relay is operated a certain number of times in succession the circuit being extended each time said relay is operated after the first two operations of said relay.

40. 20. In combination, a relay, a circuit operated thereby, a time relay arrangement for extending said circuit in one direction if said relay is operated a certain period of time, and a counting relay arrangement cooperating with said time relay arrangement to prevent the extension of said circuit in

said direction and for extending it in another direction if said relay is operated a certain number of times in succession provided the periods of operation of the relay are shorter and occur at a certain frequency. 70

21. In combination, a relay, a circuit operated thereby, a time relay arrangement for extending said circuit in one direction if said relay is operated a certain period of time, a counting relay arrangement cooperating with said time relay arrangement to prevent the extension of said circuit in said direction and for extending it in another direction if said relay is operated a certain number of times in succession provided the periods of operation of the relay are shorter and occur at a certain frequency, and means for thereafter closing said circuit in the second direction each time the relay is operated. 75

22. In a telephone system, a trunk circuit comprising a signal, means for operating said signal if battery is supplied to said trunk circuit for a certain period and for disabling said signal if battery is removed any time after said period has elapsed, and means operative when the signal is disabled for preparing a circuit that may be completed any time the battery is thereafter removed from the trunk circuit. 80

23. In a telephone system, a trunk circuit comprising a signal, means for operating said signal if battery is supplied to said trunk circuit for a certain period of time, means for disabling said signal if battery is removed after said period of time has elapsed, and means operative to transmit a signal indication each time battery is thereafter removed. 85

24. In a telephone system, a trunk circuit comprising a signal, a relay, a time relay arrangement for operating the signal if said relay is held operated for a certain period, a circuit, a relay arrangement for disabling said signal and completing said circuit 100 when said relay is released, means for breaking said circuit each time the relay is thereafter operated and completing it each time the relay is thereafter released. 105

25. In a telephone system, a trunk circuit comprising a relay arrangement, a disconnect signal, means for operating said disconnect signal if the trunk circuit has been extended and said relay arrangement is released by the removal of a battery supply 110 of one polarity, other signals, means for repeatedly operating said other signals without operating said disconnect signal if the trunk has been extended and said relay arrangement is released by the removal of 115 this polarity of battery and alternately operated by the other polarity of battery at a certain frequency.

26. In a telephone system, a trunk circuit comprising a disconnect signal, other signals, 120

means for operating the disconnect signal if said trunk circuit is extended and battery of one polarity is removed from said means, and means for operating the other signals each time battery of the other polarity is applied in momentary alternate impulses to said two means and the trunk circuit is extended.

27. In a telephone system, a trunk circuit comprising a disconnect signal, other signals, means for operating the disconnect signal if said trunk circuit is extended and battery of one polarity is removed from said means, means for transmitting a signal indication to the extended end of the trunk circuit simultaneously with the operation of the disconnect signal, and means for operating the other signals each time battery of the other polarity is applied in momentary alternate impulses to said first and last mentioned means and the trunk circuit is extended.

28. In a telephone system, a trunk circuit comprising a disconnect signal, means for operating said disconnect signal if the trunk is extended and battery is removed from said means, other signals, and means for operating said other signals without disabling the disconnect signal if the trunk line

is extended and battery is again supplied to said first mentioned means.

29. In a telephone system, a trunk circuit comprising a relay arrangement, a disconnect signal, means for operating said disconnect signal if the trunk circuit is extended and battery is removed from said relay arrangement, other signals and means for operating said other signals if the trunk circuit is extended and the disconnect signal has been operated if said battery is again applied to said relay arrangement without disabling the disconnect signal.

30. In a telephone system, a trunk circuit comprising a disconnect signal, means for operating said disconnect signal if the trunk is extended and battery is removed from said means, other signals, means for operating said other signals without disabling the disconnect signal if the trunk is extended and battery is again supplied to said first mentioned means and means for disabling said disconnect signal without disabling the other signals when the trunk becomes disengaged.

In witness whereof, I hereunto subscribe my name this 5th day of May, A. D. 1924.

LANGFORD J. BOWNE.
